UNITED STATES PATENT OFFICE.

JOHN M. HAYS AND JOHN E. FILLMAN, OF RINGWOOD, OKLAHOMA; SAID FILLMAN
ASSIGNOR TO SAID HAYS.

DUMP-WAGON.

1,331,811.

Specification of Letters Patent.

Patented Feb. 24, 1920.

Application filed May 25, 1917. Serial No. 170,958.

To all whom it may concern:

Be it known that we, JOHN M. HAYS and JOHN E. FILLMAN, citizens of the United States, residing at Ringwood, in the county 5 of Major and State of Oklahoma, have invented new and useful Improvements in Dump-Wagons, of which the following is a specification.

The present invention relates to wagons 10 generally, and more particularly to that class thereunder known as dumping wagons.

The primary object of this invention resides in the production of a wagon primarily adapted for holding hay, wheat or 15 the like products, and wherein novel means are employed for dumping the contents of the wagon into a stacker.

With these objects in view, use is made of a tilting platform or table to which is operatively connected a novel type of operating means to facilitate the tilting of the table in opposite lateral directions in a simple and expeditious manner.

Furthermore, we aim in providing a novel 25 means for locking the table in an upright position or at various angles with respect to the vehicle, in order that the hay will be dumped in the stacker in a quick, simple and expeditious manner.

With the above and other objects in view, 30 the invention consists in the novel features, details of construction and combination of parts which will hereinafter be more fully set forth, illustrated in the accompanying 35 drawing and pointed out in the appended claim.

Figure 1 is a side elevation;

Fig. 2 is a section taken on line 2—2 of 40 Fig 1, illustrating the dumping position of the table by dotted lines;

Fig. 3 is a section taken on line 3—3 of Fig. 1; and

Fig. 4 is a view similar to Fig. 2, showing 45 a slightly modified form of operating mechanism for the table.

Referring more particularly to the drawing, in which like characters of reference refer to corresponding parts in the several views, 5 denotes a wheeled vehicle including 50 a front axle 6, a rear axle 7 and a body 8. Fixedly secured to the axles is a stationary bolster 9 arranged lengthwise of the axles and formed on its upper edge with oppositely, downwardly and outwardly inclined 55 portions 10. The member 8, generically

stated as a body portion, is here shown as of flat elongated form providing a table or platform upon which hay, wheat or the like material is supported in the hauling of the material to a stacker.

60

The chief characteristic of the present invention involves mounting of the body 8 on the stationary bolster 9 for movement in opposite lateral directions with respect to the bed of the vehicle. To this end, use is 65 made of a movable bolster 11 having its confronting edge 12 inclining outwardly toward the opposite ends of the bolster and supporting on its upper edge the body 8 of the vehicle. A pair of links 13 are disposed 70 to opposite sides of the respective stationary and movable bolsters, and terminally connected at one end to the opposite faces of the bolster through the medium of rivets or the like fastening devices 14, whereas 75 the lower end of the metal straps 13 are pivotally connected to the intermediate portion of the stationary bolster 9, and the pivotal point of the movable bolster is denoted by the character 15, supporting the body 8 to 80 the stationary bolster for opposite lateral or horizontal movements with respect to the bed of the vehicle.

Each of the respective bolsters 9 is provided adjacent the ends thereof with openings 16, the pairs of openings of one bolster alining longitudinally with the pairs of openings of the opposite bolster, serving as bearings for the spaced parallel drive shafts 17 and 18 respectively. Each of the drive shafts has mounted thereon at points inwardly of the stationary bolster pinions 19, while a pinion 20 is likewise mounted on the drive shaft 17 at a point forwardly of the respective stationary bolsters, the purpose of which will be fully set forth as the description of the invention is proceeded with. The structure so far described, is common to both forms of the invention, but now specifically referring to the preferred 90 embodiment of the invention disclosed in Figs. 1 to 3 inclusive, it will be manifest that the mechanism for operating the body 8 of the vehicle is in the form of a flexible link chain 21 connected at its terminal in 105 the openings 22 provided adjacent the ends of the movable bolster 10, and trained over the pinions 19 of the drive shafts, whereby revolving the drive shafts through the medium of the crank 23, in one direction, will 110

cause the rocking of the movable bolster 11 in a horizontal direction and in turn tilt the body 8. Upon reverse rotation of the crank, the body will assume an upright position, and upon a further turning of the crank in the same direction, the body will be tilted in an opposite direction. However, a locking pawl 24 by meshing with the pinion 20, will tend to prevent any accidental rotation of the drive shaft 17 and hold the body in a level or tilted position.

A slightly modified form of operating mechanism is shown in the modified form of the invention, reference being had to Fig. 4, wherein instead of the employment of a flexible chain, use is made of a rack bar 25 connected at its upper end with one end of the movable bolster 11 and depending therefrom and loosely extending through the guide slot 26. A locking pawl 27 is provided for locking the rack bar 25 against any accidental reciprocating movement, and in turn preventing any accidental tilting action of the body, and tending to hold the body in a level or upright position during the transportation of the vehicle. In both the preferred and modified forms of the invention, the confronting edges of the respective stationary and movable bolsters by being provided with opposite inclined edges afford a non-obstruction to the tilting action of the body.

From the foregoing description, taken in connection with the accompanying drawings, the advantages of construction and the method of operation will be readily apparent to those skilled in the art to which the invention relates, and while we have described the principles of operation of the invention, together with the device which we now consider to be the best embodiment thereof, we desire to have it understood that the device shown is merely illustrative and that such changes may be made when desired as are within the scope of the appended claim. 45

What is claimed as new, is:—

A dumping wagon comprising a body and running gear, a pair of bolsters on each of said parts, said bolsters being of wedge shape with the pointed ends of the lower pair engaging the pointed ends of the upper pair, a pair of straps carried by each of the upper pair and pivotally engaging the lower pair, said straps being located at the apexes of the bolsters, a pair of shafts rotatably mounted in the lower bolsters, pinions on said shafts, a chain engaging said pinions and having its ends connected with the ends of the upper bolsters and means for manually rotating one of said shafts. 60

In testimony whereof we affix our signatures.

JOHN M. HAYS.
JOHN E. FILLMAN.
